UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE SWITCH.

Application filed December 12, 1923. Serial No. 680,173.

To all whom it may concern:

Be it known that I, EDGAR H. CLARK, a citizen of the United States of America, residing at Richmond Hill, Long Island, in the county of Queens and State of New York, have invented certain new and useful Improvements in Telephone Switches, of which the following is a full, clear, concise, and exact description.

10 This invention relates to telephone switches and more specifically it pertains to a locking device, adapted for use in automatic and semi-automatic telephone switches of the type disclosed in Patent No. 15 1,515,735, granted to Charles L. Goodrum et al. on November 18, 1924; for holding the horizontal bar in operated position to permit the deenergization of the bar operating magnet throughout the duration of an 20 established connection.

The object of this invention is to improve the construction of such telephone switches by providing means whereby sets of active contacts are held in engagement 25 with sets of passive contacts throughout the duration of an established connection in a simple and positive manner.

In accordance with the foregoing object, a feature of the invention resides in the 30 provision of a pair of interlocking latch members whereby the operating bar and the contacts served thereby are held in operated position after the initial energization of an operating magnet therefor.

35 Another feature of the invention is the provision of a magnet armature and means whereby a pivoted member is disengaged from an associated latch member for releasing the bar and the contacts upon a subsequent energization of the operating magnet.

40 Other features and advantages of the invention will appear from the following description and by the claims appended here-
to, reference being had to the accompanying drawings in which Fig. 1 is a partial assembly view of a switching device showing the locking device in normal non-operated position; Fig. 2 is a view similar to that of Fig. 1 showing the active contacts and their operated bar locked in operated position, and Fig. 3 is a partial assembly view of the operating mechanism showing the releasing spring in operable relation with the pivoted locking member.

Similar reference characters refer to similar parts throughout the several views.

The switch structure in which this locking device is particularly well adapted for use generally consists of a plurality of active contact sets which are adapted to be moved into engageable relation with sets of passive contacts through the movement of an operating bar therefor.

60 Each set of active contacts consists of a 65 plurality of bare wires 10, 11 and 12 which are moulded into an insulating support 13 held securely at both ends of the switch frame (not shown). For each set of contacts 10, 11 and 12 there is provided an oper- 70 able insulating card 14 arranged in a suitable guiding member 9. Each set of active contacts 10, 11 and 12 threads through the insulating card 14 and extends therefrom in juxtaposition with associated grid wires 75 15, 16 and 17 which are interwoven with insulating bars, such as bar 18, shown in Fig. 1.

For each card 14 there is provided a re- 80 tracting spring 19 which is secured at one end portion on the insulating support 13 and is adapted to normally hold the card 14 and the active contacts 10, 11 and 12 served thereby out of engagement from their associated grid wires 15, 16 and 17 as 85 illustrated by the two sets of contacts shown in Fig. 1.

For each retracting spring 19 there is provided a lifting finger 20 which is secured on a rotatable bar 21 and is adapted 90 to engage and move its associated spring 19, upon each movement of the bar 21, from normal to operated position. The bar 21 is journalled at one end portion on the supporting frame 22 of an electro-magnet 23 95 and the other end on a similarly disposed frame (not shown). On one end portion of bar 21 there is provided an operating arm 24 which extends therefrom in operable relation with the arm 25 of a longitudinally movable T-shaped member 26 which in turn is disposed in operable relation with the U-shaped portion of an arm 27. This arm is secured on the armature 28 which is adapted to rotate the bar 21 and the lifting finger 20 carried thereby in response to each initial energization of magnet 23. The pivoted member 38 which is hook-shaped is arranged on a portion of the frame 22 and is adapted to latch with the T-shaped mem- 100 105 110

ber 26 when the latter member is moved by arm 27 into the position shown in Fig. 2 thereby locking the hook-shaped member 26 and the bar 21 in an operated position 5 against the resistance of the bar retracting spring 30 which is hooked on the free end portion of arm 24 and on a lug 31 of bracket 22. The hook-shaped member 38 is held in engageable relation with its associated T-shaped member 26 by means of spring 29 which is detachably fastened on a lug 5 integrally formed with hook-shaped member 38 and a lug 6 of frame 22. Upon the initial movement of T-shaped member 15 23 imparted through the energization of magnet 23, the bar 21 and the lifting fingers carried thereby remain in operated position through the interlocking of members 26 and 38, to permit the deenergization of magnet 23.

It is to be noted that the spring 32 carried by the arm 27 is arranged to normally move ineffectively over the back surface of hook-shaped member 38 and thereby assist 25 in moving the hook-shaped member 38 into engagement with T-shaped member 26. A spring 33 is provided for returning the armature 27 to normal unoperated position which is indicated by the dotted line shown 30 in Fig. 2. Upon a subsequent movement of arm 27 imparted through the energization of magnet 23 the releasing spring 32 engages the camming portion 34 of hook-shaped member 38 and moves this member out of 35 engagement from T-shaped member 26 which is returned to normal position through the tension of spring 30 acting to return the bar 21 to normal position for releasing the retracting spring 19 thereby disengaging the active contacts 10, 11 and 12 40 from their associated grid wires 15, 16 and 17, respectively.

The invention claimed is:

1. In a switching mechanism, the combination of sets of disengaged contacts, a rotatable bar, an operating magnet for said bar, an armature responsive to the energization of said magnet for operating said bar, an arm fixedly attached to said bar, a lifting bar fixedly attached to said armature, a longitudinally movable member arranged in engageable relation with said arm and said lifting bar, and means cooperating with said longitudinally movable member for retaining said rotatable bar in operated position for holding said contacts in engagement when said magnet is deenergized.

2. In a switching mechanism, the combination of sets of disengaged contacts, a rotatable bar, an arm fixedly attached to said bar, an operating magnet for said bar, an armature for said magnet, a lifting bar fixedly attached to said armature, said lifting bar being arranged to lift said arm to operate said rotatable bar when said magnet is energized to interengage said contacts, a longitudinally slideable member disposed in engageable relation with said arm and said lifting bar, and means cooperating with said longitudinally movable member for retaining said rotatable bar in operated position for holding said contacts in engagement when said magnet is deenergized.

3. In a switching mechanism, the combination of sets of disengaged contacts, a rotatable bar, an arm fixedly attached to said bar, an operating magnet for said bar, an armature for said magnet, a lifting bar fixedly attached to said armature, a longitudinally movable member disposed in engageable relation with said arm and said lifting bar, a pivotal member for engaging said longitudinally movable member for retaining said rotatable bar in operated position for holding said contacts in engagement when said magnet is deenergized, and means attached to said lifting bar for effecting a positive engagement between said pivotal and said longitudinal members when said contacts are interengaged.

4. In a switching mechanism, the combination of sets of disengaged contacts, a rotatable bar, an arm fixedly attached to said bar, an operating magnet for said bar, an armature for said magnet, a lifting bar fixedly attached to said armature, a longitudinally movable T-shaped member disposed in operable relation with said arm and said lifting bar, a pivotal hook-shaped member for locking said T-shaped member in an operated position thereby maintaining the rotatable bar operated and said contacts in engagement after said magnet has been energized, and means for effecting a positive interlocking of said T-shaped and said hook-shaped members, said means being also arranged to effect the release of said locking member when said magnet is subsequently energized.

In witness whereof, I hereunto subscribe my name this 5th day of December A. D., 1923.

EDGAR H. CLARK.
